Primary Examiner — Cynthia Ramirez
Assistant Examiner — Tamara L Hahn

(57) **CLAIM**

The ornamental design for an oral care implement, as shown and described.

DESCRIPTION

FIG. 1 is a front perspective view of an oral care implement according to a first embodiment of the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is a front perspective view of an oral care implement according to a second embodiment of the new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is an enlarged top view thereof;

FIG. 16 is an enlarged bottom view thereof;

FIG. 17 is a front perspective view of an oral care implement according to a third embodiment of the new design;

FIG. 18 is a rear perspective view thereof;

FIG. 19 is a front view thereof;

FIG. 20 is a rear view thereof;

FIG. 21 is a left side view thereof;

FIG. 22 is a right side view thereof;

FIG. 23 is an enlarged top view thereof; and,

FIG. 24 is an enlarged bottom view thereof.

The dashed broken lines illustrate portions of the oral care implement that form no part of the claimed design. The grayscale depicted in the drawings is to show contrast in appearance.

1 Claim, 12 Drawing Sheets
